UNITED STATES PATENT OFFICE.

ALBERT E. STEWART, OF FRANKLIN, NEW HAMPSHIRE, ASSIGNOR TO ACME KNITTING MACHINE AND NEEDLE COMPANY, A CORPORATION OF NEW HAMPSHIRE.

KNITTING-MACHINE.

1,194,677.

Specification of Letters Patent. Patented Aug. 15, 1916.

Application filed May 5, 1913. Serial No. 765,428.

To all whom it may concern:

Be it known that I, ALBERT E. STEWART, of Franklin, in the county of Merrimack and State of New Hampshire, have invented certain new and useful Improvements in Knitting-Machines, of which the following is a specification, reference being had to the accompanying drawings, forming part thereof.

10 This invention has reference to improvements in knitting machines and resides particularly in the pattern mechanism whereby the length and the fashioning of a stocking, and the change of yarns at various points in the knitting operation are effected or controlled.

One object of the invention is to so construct a pattern mechanism for knitting machines that its actuating device may be controlled, as to the degree of its action in operating the pattern mechanism, by means carried by the pattern mechanism and related to the devices of said pattern mechanism which act initially to operate or control the change of yarn.

Another object of the invention is to so construct a pattern mechanism that it may have a duplex action to effect the tensioning of the yarn more or less gradually during the knitting of the leg and to effect a sudden tensioning of the reinforce courses before and after the knitting of the toe.

Another object of the invention is to simplify the construction of pattern mechanisms for knitting machines.

Other objects of the invention will appear from the following description.

The invention consists in the novel construction of the pattern wheel and in the means for operating the same.

The invention also consists in the means for controlling the operation of the pattern wheel.

The invention also consists in such other novel features of construction and combination of parts as shall hereinafter be more fully described and pointed out in the claims.

Figure 1, represents a side elevation of parts of a knitting machine showing the improved pattern mechanism. Fig. 1^a, represents a sectional detail view taken on line *a—a* Fig. 1. Fig. 1^b, represents a side view of portions of the stop lever. Fig. 2, repre-

sents a plan view of portions of the same. Fig. 3, represents an end view, partially in section, as taken on line 3—3 Fig. 1, of portions of the pattern mechanism showing its relation to a well known toe and heel pattern mechanism. Fig. 3^a, represents a detail view of the actuator and the release tripers for controlling the operation of the splice yarn changer. Fig. 4, represents a sectional view as taken on line 4—4 Fig. 2, showing portions of the needle and skeleton cylinders, the driving gear therefor, and the means for lifting the needle cylinder. Fig. 5, represents a sectional detail view of portions of the needle cylinder and its lifting device as taken on line 5—5 Fig. 2 to show the connection with the actuating slide rod for the cylinder lifter ring. Fig. 6, represents a detail view of the means for operating said slide rod from the pattern wheel. Fig. 7, represents an enlarged plan view of parts of the device as taken on line 7—7 Fig. 3.

Similar characters of reference designate corresponding parts throughout.

As shown in the drawings 5 indicates the bed plate of the machine frame having the cam ring supporting member 10, which has the depending flange 11 furnished with the opening 12 and provided at its lower end with the collar or flange 13 formed in part with the cylindrical bearing 14 for the needle cylinder 15 which is rotatably supported on the ring 16 having at its lower edge the usual cams 17, 17 which are complementary to cams on the ring 18 rotatably supported on the collar 13 and having the operating lever 19 which extends through opening 12 of the depending flange 11 and is operated by rod 20 slidably mounted in the machine frame. The operation of raising and lowering the needle cylinder is effected by the sliding of rod 20 to cause the partial rotation of cam ring 18. The operation of rod 20 in one direction is effected by its spring 21.

Frame member 6 has the stud shaft 22 on which is rotatable the sleeve 23 of a bell crank lever having the upwardly extending arm 24, engaging with rod 20, and the horizontal arm 25 having at its outer end the set screws 26 and 27 which respectively rest on the ends 28 and 29 of levers 30 and 31 which are pivotally mounted on a stud extending

100

from the frame and have the riding members 32 and 33 which are related to the pattern mechanism.

The pattern mechanism which controls the lifting and lowering of the needle cylinder or the fashioning of the stocking by or through the tensioning of the yarn comprises the wheel 34 which is rotatable on the shaft 35 of the usual and well known toe and heel pattern mechanism indicated as a whole at 36 Fig. 3 and more particularly described in U. S. Patent to A. N. Ames, No. 962,291, dated June 21, 1910. This pattern wheel 34 has a toothed periphery which is engaged by pawl 37 pivotally mounted on the machine frame and said wheel has a radially graduated face, each tooth and graduation being relative to the knitting of five courses of yarn under assumed conditions as will hereafter be described. At spaced distances on the face of said wheel are formed threaded sockets 38 adapted to receive the holding screws 39, 40 or 41 of the cam plates 42, 43 or 44 as the case may be. The face of pattern wheel 34 is also furnished with the outwardly extending ring 45 having a large number of radial bores in which are slidable the pins 46, 46 which have seats 47 and 48, see Fig. 3, to receive the spring pressed latches as 49 located in bores in said ring 45 which latter bores intersect the bores or guides of the pins 46, 46. By reference to Fig. 3 it will be seen that by partially rotating the pins 46, 46 the plain peripheries 35 of said pins are brought to position to receive the thrust of said latches as 49 and in such position, the pins 46, 46 may be adjustably moved radially in their bearings while when said latches as 49 are located in 40 the seats 47 or 48 of said pins 46, 46 said pins are held in the adjusted position. Provision is made to engage a tool with said pins 46, 46 by furnishing said pins with perforations 50, 50 whereby when a tool is engaged therewith said pins may be rotated and moved in their guides.

Adjustably mounted on the ring 45 are the tensioning cams 51 and 52 which are adapted to act respectively against the riding members 32 and 33 of the levers 30 and 31, cam 51 acting only on member 32 and cam 52 being shaped to clear said member 32 and act on member 33. It is of course obvious that cam 52 may be removed but, under ordinary conditions, both of said cams 51 and 52 are employed, cam 51 being related to the general tensioning of the yarn or work while cam 52 is related more particularly to the sudden tension of the reinforce courses usually desirable before and after the knitting of the toe of a stocking.

Mounted to swing on the shaft 35 adjacent the hub of wheel 34 is the lever 54 having at its free end the segmental toothed member 55 having the pin 56 on which is

pivotaly mounted the pawl 57 one end of which is adapted to be held in engaging relation with the teeth on the periphery of said pattern wheel 34 by the spring 58 secured to said pawl 57 and to a relatively fixed part of the machine. Frame member 7 has the stud 59 on which is mounted to swing the lever 60 having the toothed quadrant 61, which is engaged with the toothed member 55 of lever 54, and at its free end the pin 62.

As the levers 54 and 60 with pawl 57 form the direct means for effecting the intermittent rotation of the pattern wheel 34 it is evident that the distance through which the pattern mechanism of said wheel is moved at each forward movement of pawl 57 will depend largely upon the distance through which said pawl is moved and that by or through the adjustment or the limitation of the movement of pawl 57 the speed at which the pattern is used up and the length of the stocking may be determined.

The mechanism for operating lever 60 is actuated through the usual quadrant shaft 63 which is similar to that shown in said patent to A. N. Ames. The frame hub 8 in which said shaft is journaled, see Fig. 3, has a socket forming a guide for the spring pressed pin 64 which is adapted to engage 95 any one of several seats in the member 65 (forming in effect a ball clutch connection), which member 65 is rotatable on said shaft 63 and at its periphery has the teeth 66 and 67 which alternately differ in depth toward 100 the axis of said member 65. Fixed on said shaft 63 is the collar 68 having the arm 69 carrying the pivoted pawl 70 the free end of which is adapted to ride on the teeth 66 and 67 of member 65 and to engage the 105 shoulders of said teeth to rotatively move said member 65, against the action of the clutch connection formed by the yielding member or spring pressed pin 64, for the full throw of said pawl 70, at which time 110 another of the seats in member 65 is brought into position to be engaged by pin 64 and said member is thus held from accidental rotation, backward or forward. Journaled in said shaft 63 is the sleeve 71, which is 115 located between collar 68 of the pawl arm 69 and the ring 72 secured to said shaft 63. The sleeve 71 has the enlarged shoulder 73, which at the sides is extended to form the members 74 and 75 of which member 74 has 120 the plate 76 secured by the screw 77 and having its outer surface located within the radii of the teeth 67, 67 of member 65, while member 75 has a transverse perforation to receive the adjustable stop pin 78. Mounted 125 on said sleeve 71, between ring 72 and shoulder 73 is the collar 79 of arm 80 having the lip 81 which is adapted to be engaged by the pin 78 so that when plate 76 is engaged by pawl 70, to move its members 74 and 75, said 130

pin 78 engages lip 81 and effects the swinging of arm 80 a similar distance. Arm 80 is connected by the pivoted rod 83 with pin 62 of quadrant lever 60 which latter actuates lever 54 carrying pawl 57 which, as above stated, is engaged with the pattern wheel 34 and the distance through which said pattern wheel is moved or advanced at each forward movement of pawl 57 will depend upon the distance through which the free end of said lever 60 is swung by the operation of arm 80 and rod 83.

Pivotaly mounted on the stud 85, which extends from the machine frame is a cam 15 lever 86 having at its upper end the follower 87 adapted to ride over any one or more of the pins 46, 46 of the pattern wheel 34 whereby lever 86 may be swung on its stud 85 more or less depending upon the degree of projection of the particular pin 46 20 acting at the time on said follower 87. The lower end of cam lever 86 is pivotally connected with the arm 88 of plate 89 which plate is in effect a bell crank pivotally 25 mounted on the stud 90 of the machine frame and having the stops 91, 92, and 93 located relatively to the stud 90 and to the movement of pin 62 of quadrant lever 60 so that when one of said stops 91, 92 or 93 is positioned in the path of said pin the movement of said pin 62 and of its lever, in this direction, may be limited. Spring 94, connected to said bell crank plate 89 and to a fixed part of the machine tends constantly 30 to swing upward the free end of said bell crank while the outward movement of follower 87, or the upper end of lever 86 acts to swing the free end of said bell crank downward, against the action of said spring 94, to locate one or the other of said stops 91, 92 or 93, as the case may be, in the path of pin 62.

The relative location of the stops 91, 92 and 93 determines the distance to which pin 45 62 may be moved at each operating movement of arm 80 and hence, this determines the swinging of quadrant lever 60 in one direction and of lever 54 in the other direction whereby the retractive movement of lever 54, being proportioned to the throw of lever 60, will carry pawl 57 backward a distance equal to the length of one or more of the teeth on the periphery of the pattern wheel and the forward movement of said pawl will 50 be from its adjusted point of its retraction forward to a fixed limit of movement. While no limitation is herein placed on the location of the stops 91, 92 and 93, I prefer to so locate said stops respectively that stop 55 91 permits the retractive movement of said pawl 57 a distance of six teeth of the pattern wheel, stop 92 a distance of three teeth, and stop 93 a distance of one tooth. If, therefore, all of the pins 46, 46 are retracted the 60 follower 87 of lever 86 will ride on ring 65 45

of the pattern wheel and, as a result stop 93 will be positioned to intercept pin 62 of lever 60 so that at each action of its operating mechanism the pattern wheel 34 will be advanced one tooth corresponding to five courses of knitting. If one of said pins is projected so that its seat 47 is engaged by its pin 49 then follower 87 in riding over said projected pin will swing bell crank 89 to bring stop 91 to position to intercept pin 62 and lever 60 will effect the retraction of pawl 57 a distance of six teeth, or thirty courses of knitting, while if said pin 46 is projected so that its seat 48 is engaged by its pin 49 the result will be that the pattern wheel will be advanced, at one point, a distance of three teeth corresponding to fifteen courses of yarn. The more the pins 46, 46 are projected the more pawl 57 is retracted and therefore the pattern wheel is the more rapidly used up or rotated. When all of said pins 46, 46 are fully retracted the pattern wheel is rotated at its slowest and, hence, effects the longest pattern. It will thus be seen that the driving or advancement of the pattern wheel or mechanism is adjusted and controlled by mechanism carried by the pattern mechanism or wheel and that said wheel may be advanced rapidly, at any one or more points in the process of 95 knitting so that a tensioning movement of the knitting cylinder may be effected by reason of the gradual advancement of the pattern wheel and its cam 51 relative to the lever 30 while, if a short stocking is to be 100 knitted or it is desired to shorten the knitting at any one or more points, one or more of the pins 46, 46 is adjusted accordingly.

During the knitting of the heel and toe courses, or, it may be, at other times it is 105 sometimes desirable to prevent the operation of the pattern wheel or mechanism and for this purpose I provide the lever 96 pivotally mounted adjacent the lower end of lever 86 and having the tooth 97 and the overbalanced end 98 which, when unsustained, is adapted to swing to position to prevent the forward movement of pin 62 of quadrant lever 60. Lever 86 at its lower end has a bore to receive the spring pressed pin 99 110 which is furnished with the hold out 100 adapted to be received by a socket of said lever 86 and said pin is so positioned that, when projected, it may engage the tooth 97 of stop lever 96 whereby when lever 86 is 115 swung, as by its follower riding on a high pin 46 stop lever 96 is swung by the action of pin 99 on said tooth 97. As another means for bringing the end 98 of lever 96 into position to intercept pin 62 of quadrant arm 60 120 I provide the rear end of said lever 96 with pin 101 which is engaged in the slot 102 of rod 103 which latter is pivotally connected with rod 104 corresponding to the arm or member *h* of said patent to Ames. Shaft 125 130

105 is journaled in a bearing of the machine frame and has the tripper 106 adapted to be swung by the action of any of the cam plates or slugs 42, 42 against the free end of said tripper during the rotation of the cam wheel. On said shaft 105 is mounted the lever 107 having the member 108, and connected with the rod 109 slidably mounted and engaged, as a holding device, with the member 110 of any ordinary yarn changer mechanism which, in the present instance, is reset or raised to receive said holding rod 109 by the cam 111 of the needle cylinder drive shaft 112 which shaft is also provided with the lifting cam 113 for the yarn changer slide rod 114 having the member 115 adapted to be engaged and supported by the lever 116 pivotally mounted on the bed of the machine. This latter lever, 116, is engaged by the shoulder 117 of the slide rod 118 which is drawn in one direction by its spring 119 and is retracted against the action of said spring by the bell crank 120 pivotally mounted on the machine and connected by rod 121 with member 108 of lever 107. It will thus be seen that the swinging of tripper 106 by one of cams 42 of the pattern wheel effects the release of rod 109 from its holding out relation to the yarn changer member 110 and, at the same time, retracts slide rod 118 to permit of the engagement of its related lever 116 with the member 115 of the yarn changer slide rod 114. When slide rod 118 is retracted lever 116 is swung to position to engage said member 115 by a spring.

Provision is made to detain slide rod 118 in its retracted position until its operation is desired. It will be noticed that the end of said rod 118 is slidable transversely through a bend in said rod 109 and adjacent this point of the machine is journaled the stud 122 having the holding arm 123 which when swung downward intercepts the end of said rod 118. On said stud 122 is fixed the tripper 124 having the shoulder 125 adapted to be engaged by the pivoted spring latch 126 to sustain said tripper 124 and said stop arm 123 in the raised or inoperative position against the action of its spring 127. This upward movement of tripper 124 is effected by the passing of a cam slug 43 of the pattern wheel under said tripper while the release of tripper 124 from its holding latch 126 is effected by the operation of tripper 128 which is pivotally mounted on said stud 122 and has the inclined edge 129 which bears against latch 126 and, when moved upward by cam slug 44, effects the movement of said latch out of engagement with the shoulder 125 of tripper 124 whereby spring 127 is permitted to swing downward arm 123 to intercept slide rod 118 and hold said rod against the action of its spring. On the next, subsequent, upward movement of arm

123 slide rod 118 is operated by its spring and swings lever 116 out of holding relation with the yarn changer member 115. It is of course evident that the cam slugs 42, 43 and 44 should be so shaped as to act solely on the trippers 106, 124 and 128 respectively related thereto and to clear any and all other of said trippers.

Each rotation of the pattern wheel represents the complete cycle of operation of knitting a stocking whether said stocking be long or short, and said pattern wheel controls not only the length of a stocking but the tensioning of the yarn at any particular point in the knitting operation as well as the yarn changing mechanism whereby the tensioning of the yarn may be effected with particular relation to the change of yarns if it be desired. During the intermittent rotation of the pattern wheel 34 the needle cylinder is moved at intervals determined by the cams 51 and 52, or by one of said cams, to effect the tensioning of the yarn and the fashioning of the stocking from the top until the heel is reached. It is therefore evident that the length of the stocking will be determined by the rapidity with which the pattern wheel is rotated and that the tensioning of the yarn will be in proportion to the length of the stocking. Assuming that during the rotation of the pattern wheel the distance of one of its peripheral teeth five courses of yarn are knit then the relative tensioning of the yarn will be effected at the completion of each five courses of knitting but, if the pattern wheel be advanced a distance of five teeth during the knitting of said five courses cam 51 will permit the movement of the riding member 32 of lever 30 a proportional amount so that the fashioning of the stocking at this point will be relatively rapid. Cam 51 first engages member 32 of lever 30 at the high point of said cam and permits the gradual inward movement of said lever to permit the downward movement of the needle cylinder 110 while cam 52 is shaped to clear said lever end 32 and, before and after the knitting of the toe, to tension the reinforce courses, to engage the member 33 of lever 31 to push outward this end of said lever 31 and, through the mechanism connected therewith, to suddenly raise the needle cylinder.

Having thus described my invention I claim as new and desire to secure by Letters Patent.

1. A knitting machine having a control wheel, a pivoted arm having a pawl to rotate said wheel, a pivoted lever for operating said pawl arm, yieldable actuating means for said lever, an abutment movably mounted relative to said lever, and means controlled by said wheel for moving said abutment to limit the operation of said lever.

2. A knitting machine comprising a control wheel, a pivoted arm having a pawl to

rotate said wheel, means for operating said arm, movable means having a series of stops for intercepting said operating means, a lever for operating said movable means, and 5 an actuator for said lever adjustably mounted on said wheel.

3. A knitting machine comprising a control wheel having a series of radially adjustable control members, a lever pivotally mounted and adapted to be actuated by one or more of said members when projected, an abutment pivotally mounted and operatively connected with said lever, and means for operating said wheel including an oscillatory 10 shaft, a pawl and ratchet operated member mounted thereon, and means actuated by said latter member and adapted to be intercepted by said abutment at times.

4. A knitting machine comprising a control wheel, a swinging arm having a pawl to rotate said wheel, a second swinging arm to actuate said pawl arm, a movable abutment adapted at times to intercept said second arm, means for moving said abutment, a 25 control member radially adjustable on said wheel and adapted to act against said abutment moving means, an oscillatory shaft and mechanism operated from the said oscillatory shaft for actuating said second arm.

30 5. A knitting machine comprising a control wheel having a series of radial guides, a

series of cylindrical control members slideable in said guides and having seats at their side portions, and a series of spring pressed locking devices adapted to engage said seats whereby said members when rotated will 35 force said devices away from the engaging position.

6. A knitting machine comprising a yarn changing mechanism having a hold back 40 member, a hold back for said member, a tripper for operating said holdback to the release position, a latch for engaging said tripper, and a second tripper for releasing said latch, in combination with a control 45 wheel having a pair of cams adapted to actuate said trippers.

7. A knitting machine comprising a yarn changer slide rod, a yarn changer member, means for simultaneously retracting said rod 50 including a swinging tripper, a tripper actuated holdback for said slide rod, a latching device for holding said hold back in the open position, and a tripper for releasing said latching device, in combination with a control 55 wheel having cams for actuating said tripper mechanisms.

ALBERT E. STEWART.
